UNITED STATES PATENT OFFICE

164,293

PROJECTOR

Harold G. Fitz Gerald, Los Angeles, Calif.

Application April 30, 1951, Serial No. 15,022

Term of patent 14 years

(Cl. D61—1)

To all whom it may concern:

Be it known that I, Harold G. Fitz Gerald, a citizen of the United States, residing at Los Angeles, in the county of Los Angeles and State of California, have invented a new, original, and ornamental Design for a Projector, of which the following is a specification, reference being had to the accompanying drawings, forming a part thereof.

Fig. 1 is a side elevation of the projector, showing my new design, as viewed from the right side; Fig. 2 is a front elevation thereof; Fig. 3 is a top plan view thereof; Fig. 4 is a rear elevation; Fig. 5 is a side elevation as viewed from the left side thereof; and Fig. 6 is a bottom plan view of the projector.

I claim:

The ornamental design for a projector, as shown.

HAROLD G. FITZ GERALD.
